CLAIM

We claim the ornamental design for a storage container for a disc-shaped item of recorded media, as shown and described.

DESCRIPTION

FIG. 1 is a perspective view of a storage container for a disc-shaped item of recorded media showing our new design;

FIG. 2 is a top plan view of the storage container;

FIG. 3 is a front view of FIG. 2;

FIG. 4 is a right side elevational view of FIG. 2;

FIG. 5 is a left side elevational view of FIG. 2;

FIG. 6 is a rear elevational view of FIG. 2;

FIG. 7 is a bottom plan view of FIG. 2;

FIG. 8 is a top plan view of the first embodiment of the storage container in an open condition;

FIG. 9 is a perspective view of a second embodiment of the design shown in FIG. 1;

FIG. 10 is a top plan view of the second embodiment of the storage container;

FIG. 11 is a front elevational view of FIG. 10;

FIG. 12 is a right side elevational view of FIG. 10;

FIG. 13 is a left side elevational view of FIG. 10;

FIG. 14 is a rear elevational view of FIG. 10;

FIG. 15 is a bottom plan view of FIG. 10; and,

FIG. 16 is a top plan view of the second embodiment of the invention in an open condition.
